UNITED STATES PATENT OFFICE.

HARRY LUNDGREN, OF OAKLAND, CALIFORNIA, ASSIGNOR TO FULCHER PULP BOTTLE COMPANY, OF OAKLAND, CALIFORNIA, A CORPORATION OF CALIFORNIA.

METHOD AND APPARATUS FOR FORMING HOLLOW WARE.

Application filed March 16, 1921, Serial No. 452,814. Renewed November 1, 1926.

This invention relates to a method and apparatus for producing containers, formed from pulpy material.

Heretofore efforts have been made to form containers from paper pulp and like material, but in most instances the mechanisms designed have been cumbersome and ineffective in their operation, and have produced containers which were not perfectly formed, and in many instances could not be readily removed from the machine without rupture and distortion. It is the principal object of the present invention to provide a method and means whereby containers may be rapidly and accurately formed from plastic and pulpy material by a commercially profitable process.

The present invention contemplates the use of a carrier, upon which a plurality of forming and extracting dies are mounted, and which dies cooperate with reciprocating cores and a pulp feed mechanism to successively form containers, bring about the extraction of water therefrom, and thereafter insure that the containers will be loosened and readily removed from the core and the mold.

The invention is illustrated by way of example in the accompanying drawings, in which:

Figure 1 is a view in side elevation showing the present invention.

Fig. 2 is a view in plan showing the machine as disclosed in Fig. 1.

Fig. 3 is an enlarged view in horizontal section and elevation, disclosing one of the molds.

Fig. 4 is an enlarged view in vertical section, disclosing a mold and its operating mechanism.

Fig. 5 is an enlarged view in elevation showing the face of one of the mold dies.

Fig. 6 is an enlarged view in transverse section through one of the mold dies.

Fig. 7 is a schematic view disclosing the sequence of operation of the molds.

Referring more particularly to the drawings, 10 indicates an annular base, above which a circular turntable 11 is disposed, said turntable revolving around a vertical center shaft 12 extending upwardly from the base. The upper end of this center shaft is fitted with a spindle turret 13, which revolves with the turntable. These members are caused to rotate around the center shaft 12,

due to the driving action of a gear 14 in mesh with a circular gear rack 15 secured around the edge of the turntable, as shown in Fig. 1. The gear 14 is mounted upon a shaft 16, which is driven by any suitable mechanism.

Mounted upon the turntable 11 and spaced equidistant therearound are mold units 17. These units cooperate with reciprocating cores 18 carried upon the turret 13 to form a desired container. Reference being had to Figs. 3 and 4, it will be seen that the units comprise a cylindrical casing 19 within which radial guideways 20 are secured. These members serve as guides for the base plates 21 of dies, by which a container is molded around one of the cores 18. The base plates 21 are fitted with horizontal extensions 22, which slide along the guideways 19 when the base plates are being advanced or retracted relative to the center of the mold. The vertical faces of the guides are formed with dove-tail grooves 23, providing a way for a spline 24 formed upon the back of the die members, and by which the dies are detachably secured in position.

As illustrated in the drawings, it is intended to mold a substantially cylindrical container having a slight taper to its side wall. It will be understood that various other shapes of containers might be produced by providing other forms of dies and cores.

As shown in Fig. 3, four dies are required, a pair of oppositely disposed dies 25, and a pair of filler dies 26. The filler dies are formed with their vertical edges tapered to provide inclined back portions against which overlapping edges of the dies 25 may be disposed. The angle of the meeting faces between the backs of the dies 26 and the overlapping edges of the dies 25 is such as to cause these faces to be continuously in engagement as all of the dies are simultaneously moved in and out by the action of their base plates 21. The inner faces of the dies represent sections of a circle of the diameter of the outside of the container to be formed. Thus as the dies are simultaneously forced inwardly around the core 18, their inner faces will finally be brought to assume a complete circle. However, at all times during the movement of the dies, they will fit and move relative to each other in a manner to produce a container into which pulp may be held.

In the machine here disclosed it is possible to obtain a maximum extraction of moisture from the pulp during the forming operation. This is brought about by the manner in which pressure is exerted upon the dies and also the detailed formation of the dies as shown in Figs. 5 and 6.

It will thus be seen that the pressure faces are represented by perforated walls 27, 10 These walls are mounted on arcuate ribs 28 of the die back 29. As shown in Fig. 5 the ribs are equally spaced and extend transversely of the back. It is also desirable to incline them at a slight angle so that suitable 15 drainage will be brought about. Outlet ducts 30 are formed through the back plate and communicate with the grooves between the ribs. This will make it possible to carry off the moisture extracted by the 20 pressure of the pulp.

The bottom of the container in the present instance is formed integral with the body portion thereof, and for that purpose a perforated bottom die 31 is reciprocably mounted beneath the dies 25 and 26 and to operate with the end of the core 18 to exert pressure upon the pulpy material therebetween.

Movement of the dies 25 and 26 is brought about by a series of plunger rods 32, which 30 extend through vertical bearings 33 in the bottom of the mold housing 19. The lower ends of these rods are formed with bearing yokes to receive cam rollers 34. The upper ends of the rods are pivoted to links 35, 35 which links are secured at their upper ends to pressure rods 36, are in vertical alignment, and are disposed above the plunger rods 32. Toggle links 37 are pivoted to pins 38, carried at the opposite sides of said rods, 40 one set of said pins being disposed at the upper end of a rod and the other near the lower end thereof. The toggle links extend in opposite directions from the rod, one set connected by a pivot 39 with the back plate 21 of a die. The opposite set is secured by its outer end to pivot pins 40 carried by the mold housing 19. As shown in Fig. 4, oppositely extending toggle links are disposed above and below the extension 22 50 of each of the die back plates, and in equal spaced relation to this extension. By vertical reciprocation of the pressure rod 36 it will thus be possible to swing the links in a manner to advance and retract the dies in 55 a horizontal plane and to directly and uniformly apply pressure to the dies.

The lower die 31 is mounted within a cylindrical case 41, disposed beneath the center of the mold. This case is formed with 60 a central downwardly extending bearing portion receiving a plunger 42 fitted with a cam roller 34 as previously described for the plungers 32. Shoulders are formed upon each of the plungers 32 and 42 to provide 65 a surface against which expansion springs

43 may act. These springs will at all times tend to hold the plungers in their lowermost positions, and the rollers against cam tracks to be hereinafter described.

The pressure of the various dies is brought about by movement of the plunger rods 32 and 42 as their rollers 34 pass along cam tracks 44. Five of these tracks are arranged concentric round the center pin 12 and upon the base 10, and thus actuate the four 75 plunger rods 32 of the dies for each mold and the central plunger rod 42 for the bottom die of each mold. Each of the tracks is formed with a series of swells as indicated in Fig. 7. The first swells A are of short duration and tend to force the die members in around the core to initially work the pulp and distribute it to form a container wall of uniform thickness. The second set of swells B gradually force the die members in, and thereafter release the pressure on the dies. There are a plurality of the swells 80 B which act to work pulp and produce a thorough extraction of the moisture therefrom. After this operation the tracks are formed with swells C, which only act to produce pressure on pairs of opposing dies at 85 each mold. This action tends to strip the fiber and to slightly distort the container relative to the core so that it will be loosened 90 and may be easily removed.

The cores 18 are carried upon the spider 13 and are directly mounted at the lower ends of vertically slidable spindles 45. These spindles are formed with key ways 46, receiving splines carried on the star wheels 47, which operate to intermittently rotate the spindles and the cores at certain intervals during action of the machine. The star wheels are mounted on the upper face 100 of the spider 13 and are held against longitudinal movement relative to their spindles by the bases of supporting brackets 48. These brackets extend vertically and guide the upper ends 49 of the core spindles. 105

The core spindles are adapted to be reciprocated in synchronism with the movement of the turntable and the various molds. This reciprocating action is brought about 110 by cam tracks 50 which are secured to a fixed cam frame 51. As shown in Fig. 1 a rise is made in the cam track to support a die, while it is passing a filling station, and to thereafter permit the die to be lowered into 115 the mold as the turntable moves one-eighth of a revolution. The lifting action is brought about by engagement of cam rollers 52 with the track.

The intermittent rotation of the dies relative to their longitudinal axes is brought 120 about by pins 53, which are stationed at intervals of one-eighth of the circumference of the member 51 to be engaged by teeth of the star wheels 47, thus rotating the star wheels 125 and the dies. 130

Referring to Fig. 4, it will be noted that the lower ends of the spindles 45 are formed with shoulders 54 a short distance above the upper faces of the cores. The spindle is then reduced in diameter to pass through a cover plate 55. This cover plate is held against the shoulder 54 by an expansion spring 56. The body portion of the cover plate is circular, and snugly fits within the mouth 57 of mold plate 58. A lip 59 of reduced diameter is formed at the lower edge of the cover plate and in the present instance provides an annular recess at the mouth of the container being formed. The upper end 15 of the die slides within a central bore of the plate.

Pulp is fed into the molds automatically as they reach a feeding position indicated in the present instance as directly in alignment 20 with the spur driving gear 14. This mechanism comprises a measuring device 59 in communication with a supply of pulp through an inlet spout 60. The measuring means consists of a circular case 61 disposed 25 with its central axis horizontal and receiving a rotating measuring valve 62. This valve is formed with a central recess 63 normally turned upwardly to receive a supply of pulp from the inlet member 60. The valve may 30 be rotated by a gear 64 secured to a spindle, which spindle extends through the center of the valve. A vertically moving rack 65 is in mesh with the gear 64 and is slidably supported in a vertical guide member 66. The 35 lower end of this rack carries a roller 67 which may successively ride over cam members 68. As shown in Fig. 1 these cam members are disposed adjacent the various molds and are fixed to the turntable so that as each 40 of the molds passes the feed mechanism, a feed cam will lift the member 66, thereby rotating the valve 61 and causing the cavity therein to turn downwardly and dump the pulp into a feed spout 69. Referring to Fig. 45 7, it will be seen that this spout directly conveys the pulp into the mouth 57 of the mold.

The operation, broadly considered, consists in successively pressing a mold with its dies retracted to the feed means, where a 50 measured quantity of semi-solid pulp will be placed in the mold, after which the core will be projected into the mold. At this time the dies will initially move in around the core, thereafter retracting and moving in around the core as the mold proceeds, while between each compression the die is 55 rotated one-eighth of a turn without being withdrawn from the mold. The pressure exerted upon the pulp by the dies will be 60 progressively prolonged in its duration, after which the wall of the containers will be stretched and the containers thereafter removed from the mold and the die.

By reference to Fig. 2 it will be evident 65 that there might be eight stations of opera-

tion in the present machine, as there are eight molds disposed around the circular turntable. The number of stations are, however, determined by the saturation of the pulp with moisture, the nature of the pulp, 70 and the difficulty in producing a desired extraction of the moisture therefrom. In any event it is assumed that the various sets of cams B shall be successively lengthened, so that each compression operation will be prolonged and the moisture gradually and firmly forced from the pulp. Assuming that station 1 is represented by the position of the pulp feeding mechanism, a mold will 75 pass to this station, at which time the feed 80 cam 68 associated with that particular mold will encounter the feed rod 65, forcing up on this rod and rotating the measuring member 62, so that the contents of the measuring device may be dumped into the feed spout 85 and thereafter conveyed into the open mold. As this filled mold moves to the second station, represented by one-eighth of a revolution of the turntable, the die lifting mold 90 52 will encounter the inclined portion of the cam 50, and the core 18 corresponding to the particular mold will be gradually lowered into the filled mold. As this lowering action proceeds the filler plate 55 will follow the core through the opening 57, thereafter fitting snugly therein to prevent the pulp from forcing out. As the rollers 34 of the plunger rods 32 and 42 encounter the first set of cams A, a short initial pressure will be exerted on 95 the pulp by the dies. This pressure, as will be understood, is brought about by upward movement of the plungers 31 against their links 35, thereafter swinging the pressure bars 36 to force the pressure links 37 into horizontal alignment and thus produce a 100 considerable pressure upon the dies as they simultaneously move inwardly around the core. As previously described, the dies are so formed that their uniform movement will cause them to continuously produce a closed 105 substantially cylindrical container.

When the rollers of the plunger rods have passed off of the cams A, the plungers will tend to follow and retract the dies. At this time the star wheel 47 of the particular core will encounter pin 53, thus rotating the star wheel and the core a portion of a revolution. After this has been accomplished the plunger rollers will gradually ride up onto 115 the first set of cams B; when the dies will be forced inwardly to produce a second pressure action on the pulp. Any desired number of sets of cams B may then be provided, it being found advantageous to increase the 120 lengths of the successive sets of these cams so that more perfect extraction of moisture can be brought about. Between pressure intervals the star wheel 47 will encounter pins 53, which will rotate the core a portion 125 of a revolution and will thus cooperate with 130

the core and the dies to work the pulp and thoroughly subject all of the container wall to a desired pressure. The extracted liquid will pass out through the various ducts 30 of the dies and will finally drain into a basin 70 disposed beneath the dies. A drain pipe 71 is connected with the various basins. During the simultaneous advance and retraction of the horizontally moving dies the 10 plunger 42 will move to force a pressure plate 72 against the bottom die 31 and form the closed end of the container. Liquid extracted from this portion of the container may drain out through a duct 73.

15 When the last set of extraction cams B have been passed the pair of dies 26 is then forced inwardly by the cams C, which action will tend to slightly stretch the fiber of the container wall and distort the same in 20 the direction of the dies 25. Rotation of the core and the container is then brought about by the star wheel when it encounters one of pins 53. This will stretch the wall of the container to a larger diameter than the core.

25 The core may then be readily removed and the container withdrawn from the mold. The wall of the container is then fairly free from moisture so that it may be readily dried under normal atmospherical conditions. If, 30 however, it is desired to hasten the drying, the containers may be placed in a suitable oven. In the event that other sized containers are used, the cores may be removed from their spindles, and the dies readily removed from the pressure blocks due to their dove-tailed connection therewith.

It will thus be seen that a very compact machine is hereby disclosed, the construction being such as to insure that a maximum 40 extraction of moisture from the pulp may be made without breaking the fibers of the pulp, at the same time insuring that the container may be removed from the mold and the die without difficulty.

45 While I have shown the preferred form of my invention as now known to me, it will be understood that various changes might be made in the combination, construction and arrangement of parts by those skilled in the art, without departing from the spirit of the invention, as claimed.

Having thus described my invention, what I claim and desire to secure by Letters Patent is:

50 1. A method of making containers from plastic material, which consists in distributing the material over the outer surface of a rigid core, and thereafter molding the material by intermittently exerting pressure thereagainst and uniformly around the core, and then stretching the material to loosen the container thus formed from the core.

55 2. A method of forming containers from plastic material, which consists in applying said material to the outer surface of a rigid

core and then gradually compressing and working the material against the core by intermittent and progressively increased pressure action by the mold members.

3. A method of forming containers from 70 plastic material, which consists in applying said material to the outer surface of a rigid core and then gradually compressing and working the material against the core by intermittent and progressively increased 75 pressure action by the mold members exerting pressure uniformly against the core and changing their position relative thereto as the molding proceeds.

4. A method of forming containers from 80 plastic material, which consists in applying said material to the outer surface of a rigid core and then gradually compressing and working the material against the core by intermittent and progressively increased 85 pressure action by the mold members exerting pressure uniformly against the core and changing their position relative thereto as the molding proceeds, thereafter acting upon the formed container to slightly 90 stretch its wall and to thus separate it from its core.

5. The process of making paper hollow 95 ware which consists in intermittently pressing paper pulp between a core and mold members to form the hollow ware, and thereafter exerting pressure upon the wall thereof to slightly stretch the same circumferentially and to thus separate the hollow 100 ware from the core.

6. The process of making hollow containers of paper pulp which consists in placing the pulp in a sectional mold, thereafter inserting a core into the mold and the pulp to distribute the pulp over the bottom and around the side of the core, then intermittently and uniformly exerting pressure between the core and the sections of the mold to shape the wall of the container and extract the moisture therefrom, and then exerting pressure by mold sections to stretch the wall of the container circumferentially and loosen it from its core.

7. A process of making containers from 115 pulpy material which consists in placing a measured amount of paper pulp within a sectional mold, thereafter inserting a core within the mold to displace a portion of the pulp and distribute it over the bottom and around the sides of the core, then intermittently exerting pressure upon the pulp by the mold sections and intermittently rotating the core and the container being formed thereon between intervals of pressure by the mold.

8. A process of making containers from 120 pulpy material which consists in placing a measured amount of paper pulp within a sectional mold, thereafter inserting a core within the mold to displace a portion of the 130

5 pulp and distribute it over the bottom and around the sides of the core, then intermittently exerting pressure upon the pulp by the mold sections and intermittently rotating the core and the container being formed thereon between intervals of pressure by the mold, said rotation representing a fraction of a revolution of the core.

9. A process of making containers from 10 pulpy material, which consists in placing a measured amount of paper pulp within a sectional mold, thereafter inserting a core within the mold to displace a portion of the pulp and distribute it over the bottom and around the sides of the core, then intermittently exerting pressure upon the pulp by the mold sections and intermittently rotating the core and the container being formed thereon between intervals of pressure by the 15 mold, and then exerting pressure upon the diametrically opposite sides of the container wall to stretch the same circumferentially 20 and separate it from the core.

10. The process of forming containers 25 from paper pulp, which consists in placing a measured amount of paper pulp in a sectional mold, thereafter inserting a solid core into the mold and the pulp to distribute the pulp to form a container having a bottom and a circumferential side wall, then simultaneously and uniformly exerting pressure directly against the pulp at the end of the core and radially against the pulp around the sides of the core, then repeating said 35 operation with progressively prolonged intervals of pressure.

11. The process of forming containers 40 from paper pulp, which consists in placing a measured amount of paper pulp in a sectional mold, thereafter inserting a solid core into the mold and the pulp to distribute the pulp to form a container having a bottom and a circumferential side wall, then simultaneously and uniformly exerting pressure 45 directly against the pulp at the end of the core and radially against the pulp around the sides of the core, then repeating said operation with progressively prolonged intervals of pressure, and partially rotating 50 the container between the intervals of pressure.

12. The process of forming containers 55 from paper pulp, which consists in placing a measured amount of paper pulp in a sectional mold, thereafter inserting a solid core into the mold and the pulp to distribute the pulp to form a container having a bottom and a circumferential side wall, then simultaneously and uniformly exerting pressure 60 directly against the pulp at the end of the core and radially against the pulp around the sides of the core, then repeating said operation with progressively prolonged intervals of pressure, and partially rotating 65 the container between the intervals of pres-

sure, and then exerting pressure by certain of the mold sections upon diametrically opposite sides of the core to stretch the circumferential wall of the container to facilitate in withdrawing the core therefrom. 70

13. A machine for making containers from paper pulp comprising a mold having sectional side walls and a movable bottom member into which mold paper pulp is poured, a solid core adapted to be positioned within said mold, means for simultaneously and intermittently producing pressure of the various mold sections against the core, and means for partially rotating the container being formed between intervals of pressure. 75

14. A machine for producing containers from paper pulp, comprising horizontally movable sectional molds, into which paper pulp is placed, vertically movable cores 80 adapted to be projected into said molds, means for simultaneously and intermittently creating pressure between the sections of the mold and the core as the said mold and core travel, and means for partially rotating the core and the container being formed thereon 85 between intervals of pressure exerted by the mold sections.

15. A machine for producing containers from paper pulp, comprising vertically movable cores adapted to be projected into said molds, means for simultaneously and intermittently creating pressure between the sections of the mold and the core as the said mold and core travel, means for partially rotating the core and the container being formed thereon 90 between intervals of pressure exerted by the mold sections, and means for stretching the wall of the container circumferentially at the conclusion of the pressure forming operations of the mold. 95

16. A machine for producing containers from paper pulp comprising vertically movable cores adapted to be projected into said molds, means for simultaneously and intermittently creating pressure between the sections of the mold and the core as the said mold and core travel, means for partially rotating the core and the container being formed thereon 100 between intervals of pressure exerted by the mold sections, means for stretching the wall of the container circumferentially at the conclusion of the pressure forming operations of the mold, and means for automatically withdrawing the core from 105 the mold. 110

17. A machine for forming paper hollow ware, comprising a continuously rotating table, a plurality of contracting mold units mounted upon said table, a plurality of cores, one for each of said units, said cores and molds moving in unison, means for successively exerting uniform pressure by the mold against plastic material distributed 115 over the surface of the core as the table rotates. 120

tates, and means for stretching the container thus formed and at the completion of the uniform pressure operations.

18. A machine for making containers from paper pulp comprising a sectional mold into which paper pulp may be placed, a core adapted to be positioned in the mold, means for simultaneously exerting pressure between the various mold sections and the core at intermittent periods and means for progressively prolonging said periods of pressure.

19. A method of making containers from plastic material, which consists in disposing the material around a core, thereafter exerting pressure against the material and core to form a container and to remove the liquid content of the material, and thereafter exerting pressure against diametrically opposite points around the container thus formed to loosen it from the core.

uid content of the material, and thereafter exerting pressure against diametrically opposite points around the container thus formed to loosen it from the core.

20. A method of making containers from plastic material, which consists in disposing the material around a core, thereafter intermittently exerting pressure against the material and core to form a container, said intervals of pressure being progressively prolonged to remove the liquid from the material, and thereafter intermittently exerting pressure to diametrically opposite points around the container to loosen it from the core.

HARRY LUNDGREN.
